DESIGN FOR A COMBINATION WOODEN TEETHING RING AND RATTLE

Kay Bojesen, Copenhagen, Denmark, assignor to
Frederik Lunning, Inc., New York, N. Y.

Application September 21, 1939, Serial No. 87,317

Term of patent 3½ years

To all whom it may concern:

Be it known that I, Kay Bojesen, a subject of the Kingdom of Denmark, residing at Copenhagen, Denmark, have invented a new, original, and ornamental Design for a Combination Wooden Teething Ring and Rattle, of which the following is a specification, reference being had to the accompanying drawing, forming part

thereof, wherein the figure is an elevational view of a combination wooden teething ring and rattle, showing my new design.

I claim:

The ornamental design for a combination wooden teething ring and rattle, substantially as shown.

KAY BOJESEN.
